UNITED STATES PATENT OFFICE.

OKLA H. HERSHMAN, OF INDIANAPOLIS, INDIANA.

DESIGN FOR A PRICE RACK.

Application filed April 9, 1928. Serial No. 26,197. Term of patent 7 years.

To all whom it may concern:

Be it known that I, OKLA H. HERSHMAN, a citizen of the United States, residing at Indianapolis, in the county of Marion and State of Indiana, have invented a new, original, and ornamental Design for Price Rack, of which the following is a specification, reference being had to the accompanying drawing, forming part thereof.

Fig. 1 is a front elevation of a price rack showing my new design; and Fig. 2 is a side elevation of the same.

I claim:

The ornamental design for a price rack, as shown.

In witness whereof, I have hereunto set my hand at Indianapolis, Indiana, this 5th day of April, A. D. one thousand nine hundred and twenty-eight.

OKLA H. HERSHMAN.
